RACK FOR SUNGLASSES OR THE LIKE

Rea Porterfield Brown, Armonk, N.Y., assignor to Foster Grant Co., Inc., Leominster, Mass., a corporation of Delaware

Filed Aug. 21, 1967, Ser. No. 3,342

Term of patent 14 years

(Cl. D80—9)

FIG. 2

FIG. 1 is an elevational view showing a rack for sunglasses according to my design;

FIG. 2 is a sectional view taken substantially along the line 2—2 of FIG. 1.

The fragmentary broken line illustration of a portion of a display stand in the figures is for purposes of illustration only.

I claim:

The ornamental design for a rack for sunglasses or the like, substantially as shown and described.
